UNITED STATES PATENT OFFICE.

CLAUDE P. HATHAWAY, OF COFFEYVILLE, KANSAS, ASSIGNOR OF ONE-HALF TO JOHN G. ROBINSON, OF COFFEYVILLE, KANSAS.

SASH-LOCK.

1,152,728.

Specification of Letters Patent. Patented Sept. 7, 1915.

Application filed May 13, 1913. Serial No. 767,345.

To all whom it may concern:

Be it known that I, CLAUDE P. HATHAWAY, a citizen of the United States, residing at Coffeyville, in the county of Montgomery and State of Kansas, have invented certain new and useful Improvements in Sash-Locks; and I do hereby declare the following to be a full, clear, and exact description of the invention, such as will enable others 5 skilled in the art to which it appertains to make and use the same.

This invention relates to new and useful improvements in window sash locks, and as its principal object contemplates the provision of a sash lock which will permit the window sashes to be raised or lowered to any desired position, and will hold them in adjusted position.

A further object is to construct the sash lock in such manner that while the lock may be readily controlled from the interior of the house or building, it will be impossible for any person on the exterior to tamper with the lock in an endeavor to raise the sashes 25 for entrance.

The above and additional objects are accomplished by such means as are illustrated in the accompanying drawings, described in the following specification and then more 30 particularly pointed out in the claim which is appended hereto and forms a part of this application.

With reference to the drawings, wherein I have illustrated the preferred embodiment 35 of my invention as it is reduced to practice, and throughout the several views of which similar reference numerals designate corresponding parts: Figure 1 is a front elevation illustrating a portion of the window 40 sashes with the sash lock of this invention in assembled position. Fig. 2 is a section on the line 2—2 of Fig. 1. Fig. 3 is a section on the line 3—3 of Fig. 2. Fig. 4 is a detail view of the perforated locking plate carried 45 on the window sashes. Fig. 5 is a section on the line 5—5 of Fig. 1. Fig. 6 is a section on the line 6—6 of Fig. 1. Fig. 7 is a section on the line 7—7 of Fig. 6.

Proceeding now to the description of the 50 drawings, the numerals 1 and 2 designate respectively the upper and lower window sashes, while the numeral 3 designates the sash wall of the window casing, designated as an entirety in Fig. 2 by the numeral 4. 55 The member 3 of each side of the window

casing is cut away immediately above and below the center line of the window to receive the upper and lower sash locks of this invention. The sash locks provided for the upper and lower window sashes are practically identical in structure, differing only in this respect, that the lock for the upper sash is slightly longer than the lock for the lower sash, as illustrated in Fig. 3. The purpose of this difference in dimensions will be obvious by reference to Fig. 3, and inasmuch as the structures are practically identical only the lower sash lock will be described in detail. This sash lock, designated as an entirety in Fig. 3 by the numeral 5, includes 60 an elongated substantially rectangular housing 6. The longitudinal wall 7 of the housing is immovable and may be held in fixed position by screws or other suitable fastening devices 8, adapted to be screw threaded 65 in the tubes 9. Internally of the housing 6 and at the opposite ends thereof are arranged plunger tubes 10 and 11, respectively disposed at the inner and outer ends of the housing. When the housing 6 is in operative 70 position in the member 3, the tube 10 extends laterally with respect to the vertical frame member 2 of the window sash, and is approximately alined with the center line thereof, being disposed so as to permit a 75 locking pin 12, slidably mounted in the tube 10, to be inserted through the perforations 80 13 of a locking plate 14, which is secured to the adjacent longitudinal edge of the sash 3. 85

As a means for normally holding the pin 90 12 in locking engagement with the plate 14 and for controlling the withdrawal of the pin to permit the window sash to be raised and lowered, this invention employs a pair of pivotally mounted lever arms 15 and 16 95 and a leaf spring 17. The leaf spring 17 is secured at one terminal to a side wall of the housing 6 by bolts or screws, as at 18, and is arcuate in shape, being of such length that it extends approximately the entire 100 length of the housing. The lever 15 is centrally pivoted on a pivot pin 19, journaled in the opposite side walls of the housing, and is disposed to permit the reduced terminal to operate through a slot formed in the 105 tube 11 and to extend into a lateral bore 21 formed in a push pin 22. The lever 16 is pivoted on a pin 23 journaled in the opposite side walls of the housing and is arranged with its inner terminal 24 in engagement 110

with the terminal 25 of the lever 15. The other terminal 26 of the lever 16 extends through a slot formed in the tube 10 and projects into a bore 27 formed in the pin 12. 5 The free terminal 28 of the leaf spring 17 bears against the lever 16 between the pivotal point 23 and the free end 26 of the lever, thus normally holding the locking pin 12 in extended position with its terminal in 10 engagement with the perforation 13 of the plate 14, as illustrated in Fig. 2. By reference to Fig. 2, it will be observed that the member 3 is provided with a recess 28 alined with the tube 10 to permit the pin 15 to be 15 fully withdrawn from engagement with the plate 14.

The actual construction of the lock being thus disclosed, it now remains to describe the operation of the several parts during the 20 manipulation of the lock to raise and lower the window sashes. It will be observed that by pushing the pin 22 inwardly, the lever 15 will swing on its pivot 15, bringing the terminal 25 nearer the walls 7 of the housing 25 6, and consequently swinging the lever 16 on its pivot 23, forcing the free end 26 away from the wall 7 of the housing 6, against the tension of the spring 17. The pin 12 is thus withdrawn from engagement with the 30 notches of the plate 14, and the window may be raised or lowered in the desired adjusted position. As soon as the pin 22 is released, the spring 17 will force the terminal 26 of the lever 16 toward the walls 7 of the housing 6, thus returning the pin 12 to a position 35 of locking engagement with the plate 14.

In reduction to practice, I have found that the form of my invention, illustrated in the drawings and referred to in the above 40 description, as the preferred embodiment, is the most efficient and practical; yet realizing that the conditions concurrent with the

adoption of my device will necessarily vary, I desire to emphasize the fact that various minor changes in details of construction, 45 proportion and arrangement of parts may be resorted to, when required, without sacrificing any of the advantages of my invention, as defined in the appended claim.

What is claimed is:

The combination with a window sash and a window casing, of a perforated locking plate secured to said window sash, a spring pressed locking pin mounted for locking engagement with said plate, a housing for 55 said locking pin, a leaf spring rigidly secured at one of its ends to the wall of said housing, its free end extending toward the opposite end of said housing and being curved downwardly, a lever pivoted at its 60 intermediate portion in said housing adjacent the locking pin, one end of said lever engaging the locking pin, its free end inclining upwardly, a second lever pivoted at its intermediate portion at the opposite end 65 of said housing, one of its ends extending downwardly and engaging the inner end of a slidable push pin, said pin mounted in said housing, the free end of said second lever extending upwardly and its end engaging the spring, the upwardly extending end of the first mentioned lever engaging the second mentioned lever adjacent its end, said spring engaging the first mentioned lever between its pivotal point and its end providing 70 means for holding said locking pin in an operative or inoperative position.

In testimony whereof I affix my signature in presence of two witnesses.

CLAUDE P. HATHAWAY.
